UNITED STATES PATENT OFFICE.

HERMAN WESTLING, OF WATERTOWN, MASSACHUSETTS.

OVERSHOE.

Application filed January 19, 1928. Serial No. 247,772.

This invention relates to footwear and more especially to overshoes of the arctic type.

In fastening an overshoe, particularly one of the low styles, there is frequently a decided tendency for the upper to wrinkle at one side or the other of the ankle, especially if an adjustable fastener is used. The present invention deals with this problem and it aims to improve the construction of fastening devices for overshoes with a view to obviating the difficulty just mentioned while still providing a fastening device that can be easily operated and producing an overshoe of pleasing appearance.

The nature of the invention will be readily understood from the following description when read in connection with the accompanying drawings, and the novel features will be particularly pointed out in the appended claims.

In the drawings,

Figure 1 is a perspective view of an overshoe constructed in accordance with this invention; and

Fig. 2 is a front view of the upper part of the overshoe shown in Fig. 1.

The shoe construction shown comprises a vamped 2, quarters 3, and a cuff 4 which is folded downwardly from the upper edge of the quarters. The shoe may be made by any suitable method and preferably has the usual bellows top.

Secured to the upper at opposite sides of the bellows top are two straps 5 and 6, respectively. Each strap carries one member of a fastening device, these members preferably being adjustable on the straps. The fastener shown is of the snap variety and comprises two members 7 and 8, the member 7 having a stud 9 designed to snap into the spring socket 10 of the member 8, this being a common type of fastener. Each fastener member has slots through which its respective strap can pass and which permit the adjustment of each member on its individual strap. It will be seen from an inspection of Fig. 2 that the straps project from under the opposite edges of the cuff 4 and that they extend diagonally in a downward direction

across the vamped of the shoe, crossing each other at a point located about midway between the forward edges of the cuff and approximately in the middle of the ankle. By snapping the two parts 7 and 8 of the fastener together they secure the straps in the relationship shown in Fig. 2 and thus fasten the shoe about the wearer's ankle. Since the fastener members are adjustable on the individual straps the wearer can set them in such positions that they will hold the top of the shoe snugly about the ankle.

This arrangement equalizes the strain on the quarters and avoids wrinkling, while at the same time permitting an adjustment which is often very desirable. The fastening device obviously is easily manipulated and the construction involves no unusual departure from the ordinarily manufacturing methods.

While I have herein shown and described a preferred embodiment of my invention, it will be understood that the invention may be embodied in other forms without departing from the spirit or scope thereof.

Having thus described my invention, what I desire to claim as new is:

1. An overshoe having a bellows top, two straps secured to the ankle portion of said top at opposite sides of the bellows portion thereof, said straps extending diagonally across the front of the overshoe and downwardly from the points at which they are secured to the overshoe and crossing each other approximately opposite the central part of the ankle, and fastening means for releasably securing said straps together where they cross each other.

2. An overshoe of ankle height having a cuff extending downwardly from the upper edge of the top of the shoe, two straps secured, respectively, at opposite sides of said top at points under the cuff, said straps extending diagonally across the front of the overshoe and crossing each other at approximately the middle of the space between the forward edges of said cuffs, and two cooperating fastening members mounted respectively on said straps and adjustable thereon, said fastening members being adapted to se-

cure said straps together where they cross each other.

3. An overshoe having two straps secured respectively to opposite sides of the ankle portion of the upper and extending diagonally across the front of the overshoe, said straps crossing each other at approximately the

middle of the ankle, and two cooperating members of a snap fastener mounted, respectively, on said straps and adjustable thereon, said members being adapted to fasten said straps releasably together at the point of intersection of said straps. **10**
